The ornamental design for a “two-way radio,” as shown and described.

DESCRIPTION

FIG. 1 is a top, front and right side perspective view of a two-way radio showing my new design;

FIG. 2 is a rear elevation view thereof;

FIG. 3 is a left side elevation view thereof; and,

FIG. 4 is a bottom plan view thereof.

The broken lines immediately adjacent the shaded portions of the design depict the boundaries of my design and form no part thereof.
